METHOD OF AND APPARATUS FOR DEHYDRATING TAR

Filed March 13, 1929

UNITED STATES PATENT OFFICE

HAROLD A. KLEINMAN, OF MOLINE, ILLINOIS, ASSIGNOR TO THE GAS MACHINERY COMPANY, OF CLEVELAND, OHIO, A CORPORATION OF OHIO

METHOD OF AND APPARATUS FOR DEHYDRATING TAR

Application filed March 13, 1929. Serial No. 346,670.

My invention particularly relates to the separation of water and some of the light oils from a tar emulsion by a process and in apparatus by which, after each batch or charge of the emulsion has been circulated and heated, the dehydrated tar and water are intermittently drawn off. The circulation is effected periodically for desired periods of time in a closed circulatory system, some of the 10 evaporated water and light oils being withdrawn continuously during the circulation of the batch, each batch being dehydrated separately and entirely and fully drawn off before another batch is charged into the separating 15 tank. The water and light oils rising to the top of the tar in the separator are also drawn off intermittently.

In those operations in which the emulsion contains a high percentage of water, so that 20 the remaining dehydrated tar occupies only a comparatively small per cent of the active capacity of the separating tank 1, the water is drawn off and the tank 1 filled to one hundred per cent active capacity with a fresh 25 batch of emulsion, without drawing off the comparatively small amount of tar of low moisture content remaining from the previous batch. This modification of the regular and normal method of operation hereinbefore 30 described presents some advantages when dealing with emulsion of high moisture content because the moisture content of subsequent batches is much less than the moisture content of the first batch and it might be 35 advantageous to leave a certain quantity of the dehydrated tar in the separating tank.

The annexed drawing and the following 40 description set forth in detail certain steps illustrating the carrying out of my improved method and certain means exemplifying an embodiment of my improved apparatus, such steps and means, however, illustrating but one of the various processes and but one of 45 the various structural assemblies by which

the principle of the invention may be carried out.

The drawing is a diagrammatic view of certain apparatus in which my improved process may be carried out and embodying 50 the several elements of my improved dehydrating means.

Referring to the annexed drawing, I provide a separating tank 1 which is intermittently charged with desirable-sized batches 55 of tar and water emulsion, this charging being effected in any desired manner and illustrated in the accompanying drawing by the valve-controlled emulsion inlet 2 connected to a pipe section 4 which enters the bottom 60 of the tank 1. The separating tank 1 is provided with a vertical series of valve-controlled test pipes 16, whereby the water which separates out in the tank 1 and rises to the top of the tar therein can be tested as to height 65 and intermittently drawn off, as desired. Through the medium of a suitable pump, such as illustrated by the centrifugal pump 3, and by pipe connections 4 and 5, the batch 70 of emulsion charged into the tank 1 is passed 75 through a heater 7 supplied with steam, the actual passage of the emulsion through the heater 7 being accomplished in any suitable manner, the means shown in the accompanying drawing being illustrative and consisting of a coil 6 connected to the pipe 5 at one end and connected at its discharge end with a pipe 8 which feeds into the top of the separating tank 1. The heater 7 is steam-heated in any desired manner and I illustrate in the so accompanying drawing two or three expedients for effecting this operation. For instance, the exhaust steam from the pump 3 is supplied through the conduit 13 to a pipe section 14 and thence conducted to the heater 85 casing 7. Exhaust steam from an outside source can be fed to the pipe section 14 which is valve-controlled beyond the connection of the conduit 13. Live steam can be fed to the pipe section 14 through the valve-controlled 90

conduit 15. The valve control for the live steam connection 15 consists of a valve member 21 which acts automatically to furnish the proper discharge pressure.

5 The tank 1 and the heater 7 and the various pipe sections mentioned form a closed circuit by means of which the emulsion is circulated or recirculated for any desired period of time. Preferably, the actual discharge of 10 the heated emulsion into the top of the tank 1 is effected through spray openings 17 formed in a pipe section 9 located in the top of the tank 1 and connected to the discharge end of the pipe section 8.

15 In passing through the openings 17, the emulsion is broken up, and the tar is separated out from the emulsion and goes to the bottom of the tank 1, the water remaining on top of the tar. The temperature at which 20 the emulsion is sprayed from the openings 17 may vary over a considerable range but is such as to effect the vaporization of part of the water and light oils under the temperature and pressure existing in the tank 1. For 25 instance, the emulsion might leave the heater 7 at about 227 degrees Fahrenheit, the pressure being about five pounds, the pressure in the top of the tank 1 being substantially atmospheric, and the temperature in the top 30 of the tank 1 being approximately 212 degrees Fahrenheit. Thus part of the water and light oils are evaporated as they pass through the openings 17 and pass off through the pipe connection 10 into a condenser 11 to 35 which cooling water is supplied. The condensed vapors pass out of the condenser 11 through a pipe 19 to the inlet 20 of the tar and liquor separator (not shown), which latter, as is well-known to those skilled in the 40 art, receives the overflow from the seals, condensers, scrubbers, tar extractors, etc., of a water gas plant. A siphon seal 23 is provided in the inlet pipe 20. However, if the pressure in the tank 1 is reduced to a point 45 lower than substantially atmospheric, the temperature at which the emulsion leaves the heater 7 and passes through openings 17 must be such that part of the water and light oils will be evaporated under the tem- 50 perature and pressure that is maintained in the tank 1. For instance, the pressure in the tank 1 can be reduced below atmospheric pressure through the medium of the valve-controlled pipe 21 and the pump 22, and the 55 vaporization of part of the water and light oils obtained, even if the temperature of the emulsion passing through the openings 17 is below 212 degrees Fahrenheit.

The circulation is continued until the desired separation of the water from the tar is effected, and then the pump 3 is stopped and the emulsion remaining in the tank 1 allowed to settle. After settling, the water is drawn off from the top of the emulsion in the tank 1 65 and the remaining tar containing but very

little water is transferred to a dehydrated tar storage tank through the medium of a valve-controlled pipe 12 connected to the pipe section 4. This pipe section 4 is also valve-controlled, between the pump 3 and the connection with the pipe 12, as shown. The water upon the top of the tar in the separator 1 can be intermittently drawn off, as desired, through the test pipes 16 or other suitably located larger discharge means.

70 The separating tank 1 is then partly filled with another batch of emulsion to the desired level and the afore-described process repeated.

I direct particular attention to the fact that by my improved method and in my improved apparatus, batches of emulsion are periodically charged into the tank 1 and a whole batch is separated to the desired extent into the dehydrated tar and water, and the separated tar and water drawn off, before another batch of emulsion is charged into the tank 1, except for the modification hereinbefore described when the emulsion contains a high percentage of water. The dehydrated tar is drawn off at the end of the circulating and settling period for the particular batch, and the separated water is drawn off intermittently, as desired. Part of the water and light oils evaporate and are taken off continuously from the separating tank during the circulating operation.

75 What I claim is:

1. A method of dehydrating tar comprising, recirculating a batch of the emulsion of tar and water through a closed system of which one portion consists in a separating sector, the water and light oils being separated from the tar in said sector; exteriorly steam-heating the emulsion each time it passes through another sector of the system, and before it reaches said separating sector, the system being maintained at a temperature of substantially 212° F., the emulsion leaving the heater at a temperature higher than that at which water boils under the temperature and pressure existing in the separating sector of the system; permitting the emulsion thus treated to settle in the separating sector after the circulatory operation; continuously drawing off evaporated water and light oils from the separating sector during the circulatory operation; and intermittently drawing off separated water and dehydrated tar from said separating sector.

emulsion and separate out the tar therefrom, the system being maintained at a temperature of substantially 212° F., the emulsion leaving the heater at a temperature higher than that at which water boils under the temperature and pressure existing in the separating sector of the system; permitting the emulsion thus treated to settle in the separating sector after the circulatory operation; continuously drawing off evaporated water and 5 light oils from the separating sector during the circulatory operation; and intermittently drawing off separated water and dehydrated tar from said separating sector.

10 Signed by me this 11th day of March, 1929.

15 HAROLD A. KLEINMAN.
